TWIN FURNITURE GLIDE

Julius B. Wilhelm, Nantasket, Hull, Mass.

Application October 6, 1958, Serial No. 52,873

Term of patent 14 years

(Cl. D10—6)

Fig. 1.

Fig. 2.

Fig. 1 is a top plan view of a twin furniture glide embodying my new design; and

Fig. 2 is a view in side elevation of the furniture glide of Fig. 1.

I claim:

The ornamental design for a twin furniture glide, as shown.
